AUTOMATIC EMISSION CONTROL CIRCUIT

Murray Bevis, Oak Ridge, Tenn., assignor, by mesne assignments, to the United States of America as represented by the United States Atomic Energy Commission

Application January 26, 1945, Serial No. 574,664

3 Claims. (Cl. 250—41.9)

This invention relates to the automatic control of electron discharge devices and it is particularly concerned with automatic control of the emissivity of a cathode. More particularly still the invention is concerned with arrangements embodying a cathode and an anode wherein an arc is struck between the cathode and the anode and this may be in an atmosphere consisting of the vapor of a solid material. The invention finds particular application in isotope separating apparatus wherein there is an ion source comprised of means for vaporizing a solid material, the isotopes of which it is desired to separate, and ionizing means consisting of a cathode and an anode between which an arc is struck in an atmosphere of the vapor of the solid material. This type of apparatus is described in detail in the prior application of Ernest O. Lawrence, Ser. No. 557,784 filed October 9, 1944. In this type of apparatus the ion source is within a space evacuated to a relatively high degree of vacuum and a relatively intense magnetic field is provided which is in the same direction, that is, it is parallel to the arc which is struck between the cathode and anode or, in other words, the arc which is struck follows the direction of the magnetic field. In this apparatus, when the vacuum is at the desired value and also the magnetic field, and the proper quantity of material is being vaporized and the cathode is emitting, an arc will be struck between the cathode and anode depending upon all of these various factors and the arc may be said to have struck when its value is one ampere, for example. A higher temperature of the cathode is required to cause the arc to strike than to sustain it after it has struck, because of low initial emissivity.

A primary object of my invention is to provide an automatic timing arrangement which periodically raises the temperature or emission of the cathode to a relatively high value for relatively short intervals until the arc is struck and then sets the temperature down to a steady intermediate value. During the period preceding striking of the arc, or attempting to strike the arc, and during which the other conditions referred to above are being adjusted and stabilized, the temperature of the cathode may be set at a relatively lower standby value. The purpose of the arrangement is to prolong the life of the cathode, which may be a filamentary cathode, by not operating it continuously at high temperature when no arc has been struck.

Another object of the invention is to provide an automatic control arrangement for periodically raising the emission of a cathode to a relatively high value for short intervals and then reducing the emission to a lower steady value in response to a relay mechanism controlled by an arc struck between the cathode and anode.

Other objects of my invention and numerous of its advantages will become apparent from the following detailed description and annexed drawing wherein the single figure is a wiring diagram of the automatic control arrangement of my invention as applied to an ion source of the type referred to above.

2

Referring to the drawing, numeral 10 designates generally an ion source of the type described in detail in the application referred to above. The ion source may be a part of the isotope separating apparatus as described in the earlier application and it is disposed within an evacuated envelope or space indicated by the broken lines 11. The ion source comprises a chamber, as indicated at 12, having an enlarged lower portion and a smaller upper portion connected by a converging throat as shown, the upper portion having an opening 13 in the form of a slit. A charge of solid material to be ionized is placed within the chamber 12 and it is vaporized by electric heating elements designated by numeral 14, the supply of heat thereto being controlled by any of various suitable types of automatic control system. Disposed adjacent one end of the slit 13 is a filamentary cathode 15 and disposed adjacent the other end of the slit and attached to the chamber 12 is an anode or anode plate 16. When the ion source is a part of the apparatus as described in the earlier application referred to, a magnetic field is provided which is parallel to the slit 13 as indicated by the arrow adjacent thereto. Vapor of the charge material in the chamber 12 passes up past baffles 17 through the narrow portion of the chamber and upwardly through slit 13. In operation a stream of electrons is emitted by the cathode 15 and they are collimated by the magnetic field and form an arc between the cathode 15 and anode 16.

My invention is particularly concerned with automatic control of the emission of the cathode 15. The cathode 15 is supplied with power from a transformer 20 having a primary winding 21 and a secondary winding 22, the flow of power to the cathode being controlled by a saturable reactor 23 which is in circuit therewith as shown. The saturable reactor is of conventional design of this type of device, it consists of alternating current windings 24 and 25 and a D. C. winding 26, the energization of which controls the amount of energy which the saturable reactor feeds to the cathode.

A suitable D. C. potential is applied between the cathode 15 and the anode 16, that is, between the cathode 15 and the chamber 12 to which the anode 16 is attached, by leads 31 and 32. Lead 32 connects to the chamber 12 through a voltage divider 33 and the other lead 31 connects to one of the leads to the cathode 15 as shown. The voltage divider 33 controls the energization of a relay 34 having a winding 35 and a switch 36 which closes when the relay is energized and this occurs when there is a predetermined current in the voltage divider 33 so as to cause a predetermined voltage to be impressed on the winding 35.

My invention is particularly concerned with the control of the energization of winding 26 of saturable reactor 23 and with automatic variation of the energization of this winding in response to actuation of the relay 34.

Numerical 40 designates generally an electronic timing arrangement comprising a pair of similar tubes 41 and 42, the filaments of which are supplied with power from the secondary winding 43 of a transformer 44 having a primary winding 45. The primary winding 45 is supplied with power by leads 46 and 47 which are connected to a suitable source of power under control of a manual switch 48 and a relay 79 which will presently be described. The secondary winding 43 supplies power to the filaments of the tubes 41 and 42 which have indirectly heated cathodes, the connection being diagrammatically designated by the characters X—X. With reference to the timing device 40, the plate of tube 41 connects to the grid of tube 42 through a condenser 50, and the plate of tube 42 connects to the grid of tube 41 through a condenser 51. In the plate circuit of tube 41 is a resistance 55 having a condenser 56 connected across it, and in the plate

circuit of tube 42 is a resistance 57 in series with a winding 58 of a relay 59 having a switch 60 which is normally open and which closes when the relay 59 is energized. A condenser 61 is connected across the resistance 57 and winding 58. Numeral 65 designates a series of resistances associated with an adjustable tap 66, any one of which can be connected so that the condenser 50 can charge therethrough when tube 41 is conducting. Numeral 70 designates a similar set of resistances having an adjustable tap 71 associated therewith whereby any one of the resistances can be connected so that the condenser 51 can charge therethrough when the tube 42 is conducting.

In the operation of the timing device 40, when the transformer 44 is energized and when tube 41 is conducting, there will be a voltage drop across resistance 55 so that its lower end will be at a negative potential which will make the grid of tube 42 negative relative to its cathode by reason of the connection through condenser 50. Tube 42 will thus be nonconducting, condenser 50 will charge through one of the resistances 65, until the grid of tube 42 is brought to cathode potential, the time required depending upon the value of the resistance which is placed in circuit. When tube 42 becomes conducting, the current flow through resistance 57 and winding 58 will cause the upper end of resistance 57 to be at a negative potential which will cause the grid of tube 41 to also be negative rendering this tube non-conducting. The current flow through winding 58 will energize relay 59 causing closure of switch 60. Condenser 51 will now charge through one of the resistances 70 until the grid of tube 41 is brought to cathode potential rendering this tube conducting, the time required for it to charge being dependent upon the resistance connected in circuit with the condenser. The tubes 41 and 42 will alternately be conducting in the manner described above, relay 59 becoming energized each time that tube 42 is conducting, the on and off periods of the relay 59 being adjustable by adjusting the taps 66 and 71, tap 71 serving to adjust the on period of the relay and tap 66 serving to adjust the off period. In my particular system the on period may be 60 seconds, for example, and the off period may be 500 seconds as will presently be referred to again.

Relay 59 controls another relay 75 having a winding 76 controlling switches 77 and 78 which are normally open but which close when the relay 75 is energized.

Numeral 79 designates another relay having a winding 80 which controls switches 81 and 82, switch 81 normally being closed and opening when the relay is energized and switch 82 normally being open but closing when the relay is energized. Relay 79 is controlled by the switch 36 of relay 34, the relay 79 becoming energized when the energization of relay 34 causes the closing of switch 36.

Switch 77 of relay 75 controls a red signal light 85 supplied with power from the secondary 43 of transformer 44, as indicated by the characters X—X. Numeral 88 designates a green signal light which is continuously connected across this same source of power. Switch 78 of relay 75 is arranged so that when it is closed it shunts two variable resistances 90 and 91 which are normally in circuit with the D. C. winding 26 of saturable reactor 23, this winding normally being supplied with power from a D. C. source by way of leads 92 and 93. Either of the resistances 90 and 91 may be shunted by manual switches 95 and 96 respectively, associated therewith. The switch 82 of relay 79, when closed, shunts resistance 90 out of the circuit of winding 26 but not resistance 91.

Switch 81 of relay 79 controls the supply of power to the transformer 44, that is, it controls the operation of the electronic timer.

In the standby operation of the system as described, the supply of power to the D. C. winding 26 of saturable reactor 23 is through both of the resistances 90 and 91, both of which are variable, so that the emission of cathode 15 is at a relatively low standby value. The D. C. winding of the saturable reactor 23, of course, controls

the degree of saturation thereof and therefore the amount of power which is fed to the cathode 15 from transformer 20. The standby value of the emission can, of course, be varied by adjusting either of the resistances 90 or 91.

When the conditions associated with the ion source 10 are such that it is desired to attempt to strike the arc between the cathode 15 and anode 16, the manual switch 48 is closed energizing the transformer 44, the switch 81 being closed at this time. This starts the timer 40 in the manner described above causing switch 60 of relay 69 to be periodically closed and to cause the relay 75 to similarly periodically close its switches. Thus the resistances 90 and 91 are periodically shunted out of the circuit of D. C. winding 26 so that the power supplied to the cathode 15 is considerably increased for intervals, that is, the intervals during which relays 59 and 75 are energized. The increased power supplied to the cathode 15 raises its emission to a relatively high value, and when the conditions associated with the ion source 10 are proper, an arc will be struck between the cathode 15 and the anode 16. When the arc has struck, and it may be said to have struck when it has a value of one ampere for example, it is no longer necessary to maintain the emission of cathode 15 at as high a value as was necessary to cause the arc to strike. When the arc strikes, there will, of course, be current in the arc circuit, that is, the circuit having in it the D. C. supply 31—32 and the voltage divider 33. Thus, the voltage will be increased across the winding 35 of relay 34 energizing this relay and closing switch 36. Closure of switch 36 will energize winding 80 of relay 79, which is connected across the power supply 46—47, and energization of this relay will open switch 81 and close switch 82. Opening of switch 81 will de-energize transformer 44 cutting off the power supply to and stopping the operation of the electronic timer 40. Thus, periodic operation of relays 59 and 75 will cease. Closure of switch 82 will shunt the resistance 90 out of the circuit of the D. C. winding 26 of saturable reactor 23 but not the variable resistance 91. Thus the power supply to the D. C. winding 26 will now be at an intermediate value which is higher than the standby value described but lower than the value it is at when relay 75 is energized and both resistances 90 and 91 are shunted. The power supply to the D. C. winding 26 will now be such that saturable reactor 23 will feed enough power to the cathode 15 to maintain its emission at a value high enough to sustain the arc between cathode 15 and anode 16. This emission can be adjusted by adjusting the variable resistance 91 which is still in circuit with D. C. winding 26 when relay 79 is energized.

The emission of cathode 15 can be raised to its maximum value at any time, of course, simply by closing both of the manual switches 95 and 96 or by closing only the manual switch 96 while relay 79 is energized.

From the foregoing those skilled in the art will observe that I have provided an efficient automatic system for preserving and lengthening the life of a cathode by controlling its emission in accordance with requirements necessary for operation. The emission is automatically raised at intervals until conditions are such as to cause the desired arc to strike. The emission is then automatically lowered to a value as necessary to sustain the arc. The arrangement provides for all of the necessary adjustments for varying the periodicity and duration of the intervals of high emission and for adjusting the values of the emission at the highest stage and in the intermediate and standby stages.

The foregoing disclosure is representative of the preferred form of my invention and it is intended that it be interpreted in an illustrative rather than a limiting sense, and that the scope of the invention be determined only in accordance with the claims appended hereto.

I claim:

1. In a control apparatus in combination, means

forming a cathode, means comprising an anode, and said cathode and anode being adapted to have an arc struck therebetween, automatic control means for controlling the emission of said cathode comprising electric circuit means which when energized renders said cathode emissive at a standby value, timing means having a periodically actuated switch interlocked with said circuit means whereby said cathode is periodically rendered emissive at a relatively high value for short intervals and means responsive to the striking of an arc between said cathode and anode for rendering said timing means ineffective to render the cathode highly emissive, and means controlled by the arc responsive means for influencing said circuit means to set the cathode emission at a steady value intermediate said standby value and said relatively high value. 10

2. In a control apparatus, in combination, means forming a cathode, means forming an anode, said cathode and anode being adapted to have an arc struck therebetween, means including an electrical circuit for supplying power to said cathode for rendering it emissive, means comprising a periodic timer including a switch which is periodically opened and closed and means including said switch whereby the power supplied to the cathode is periodically varied so as to intermittently render the cathode highly emissive for short intervals, means responsive to the striking of an arc between said cathode and anode comprising an automatically operated switch which is actuated upon striking of an arc and means interlocking said last switch with said timer and arranged to discontinue 20 25 30

action of the timer in changing the emissivity of the cathode upon actuation of the switch.

3. In a system of the character described comprising a cathode and an anode adapted to have an arc struck therebetween and having one power supply for the cathode and a second power supply for sustaining the arc, in combination, means including a circuit for supplying power to the cathode for rendering it emissive, means comprising a periodic timer controlling said circuit and having a switch interlocked with said circuit to periodically raise the emissivity of the cathode to a relatively high value, means responsive to the striking of an arc comprising a switch operative to be actuated upon striking of the arc, and means interlocking said last switch with said timer and arranged to discontinue the action of the timer to increase the emissivity of the cathode, the cathode power supply being at a relatively lower value during the periods of discontinuance of the timer action. 15
